Filed Sept. 30, 1971, Ser. No. 185,480

Term of patent 14 years

Int. Cl. D23—03

U.S. Cl. D23—97

FIG. 1 is a front view of a free standing fireplace showing my new design;

FIG. 2 is a side view of the design shown in FIG. 1, and the opposite side view is the same;

FIG. 3 is a rear view of the design shown in FIG. 1;

FIG. 4 is a top view of the design shown in FIG. 1;

FIG. 5 is a perspective view of the design shown in FIG. 1; and

FIG. 6 is a bottom view of the design shown in FIG. 1.

The mesh pattern is partially shown on the front fireplace screen for convenience of illustration, it being understood that the mesh is continuous over the area indicated.

I claim:

The ornamental design for a free standing fireplace, as shown and described.
